UNITED STATES PATENT OFFICE.

CHARLES SPORNHAUER, OF COLD WATER, OHIO.

ICE-CREAM FREEZER.

SPECIFICATION forming part of Letters Patent No. 388,925, dated September 4, 1888.

Application filed August 3, 1887. Serial No. 246,053. (No model.)

To all whom it may concern:

Be it known that I, CHARLES SPORNHAUER, a citizen of the United States, residing at Cold Water, in the county of Mercer and State of Ohio, have invented a new and useful Improvement in Ice-Cream Freezers, of which the following is a specification.

My invention relates to improvements in ice cream freezers; and it consists in certain novel features, hereinafter described, and specifically pointed out in the claim.

In the annexed drawings, Figure 1 is a perspective view of my improved device, and Fig. 2 is a central vertical section of the same.

Referring to the drawings by letter, A designates the outer receptacle or tub, having a socket in the center of the bottom, and B B are standards secured to the sides of the receptacle and projecting up above the upper edge thereof, and provided on their upper ends with the vertical projections b, having latches or buttons b' pivoted on the ends.

C designates the inner body or vessel, having a conical bottom with the apex down, and the said apex rests in the socket in the bottom of the outer receptacle, and thereby forms a journal or pivot for the inner vessel.

C' designates the cover of the inner vessel, having a central vertical opening, c, as shown.

P designates a cross-head, which consists of a single bar having notches in its ends to receive the projections b of the standards. This cross-head is rested on the upper ends of the standards, with the projections b fitting in the notches in its ends, and the buttons b' are then turned over the ends of the cross-head to secure it in place, as clearly shown in Fig. 1.

The lid or cover C is provided on its upper side around the edge with the gear-teeth K.

A central opening, c, is formed in the lid, as before stated, and a sleeve, K', is attached to the upper side of the lid and communicates with the said opening.

A bearing is formed in the upper portion of one of the standards, and in said bearing is mounted a shaft, L, having a gear-wheel, L', on the inner end to mesh with the gear-wheel K.

l designates a rigid collar formed on the shaft L, which bears against the outer side of the standard, and an adjustable collar, l', is

secured on the other end of the shaft to press against the inner side of the standard when the shaft is in place, to prevent all longitudinal play of the latter.

55

M designates a crank-arm secured on the outer end of the shaft L.

N designates a vertical shaft journaled at the upper end in the sleeve K', projecting slightly above the upper end of the latter and 6c having a squared or angular upper end.

O represents the dasher, which is secured to the lower end of the rod or shaft N, and it comprises the radial arms O', to the outer ends of which, on one side of the vertical shaft, is 65 secured the blade O², which extends down below the lower arm and is turned in and secured at the end to the lower end of the said shaft N. The dasher is formed with a twist, so as to give it the action of a screw, which draws the 70 material at the bottom of the body upwardly, so as to prevent any settlement of sugar or other heavy ingredients. The radial arms are twisted and inclined both lengthwise and laterally, and the lower inturned portion, O³, of 75 the blade O² is so disposed as to cut very close to the body and agitate those ingredients which have a tendency to settle to the bottom of a vessel. The center of the bar or cross-head is provided with a vertical opening, p, 80 through which passes the sleeve K', the upper squared end of the shaft N projecting above the upper side of the cross-head.

R represents a swinging latch pivoted to the upper side of the cross-head, and having a 85 square aperture or notch in the free end to fit the squared end of the shaft. The latter cannot turn, and consequently when the body is turned by rotating the gear-wheel L' it will turn around the dasher, which is stationary.

90 The object of constructing the device so that the rotation of the dasher may be allowed or prevented at will is as follows: It is a well-known fact that in making ice-cream, if the beating of the cream is very violent at first, before it has been thoroughly cooled by the ice, butter is very apt to be formed, which is found in lumps in the ice-cream. To prevent this I so arrange the machine that at first, before the cream is cooled, the dasher will turn with the 95 body of the freezer and almost as fast as the latter, the only hinderance being friction, and

90

100

thus the cream is not agitated much and no butter is formed. When the cream has become cooled, (which will soon happen if the body is turned with ice in the outer receptacle,) 5 the latch R is engaged with the upper end of the shaft N, and as the motion of the dasher is stopped the agitation of the cream will be very violent and all the ingredients of the ice-cream will be thoroughly mingled.

10 It will be observed that, the bottom of the inner vessel being conical, a larger space than has heretofore been provided is left at the lower corners of the outer vessel for the packing of ice. This feature of my device over- 15 comes a serious objection to the freezers heretofore provided, for it was found that when the ice was packed around the sides of the inner vessel the cream was not frozen as rapidly as when the ice was packed under the bottom of 20 the said vessel; but in the constructions heretofore devised it was found impracticable to pack ice under the bottom of the inner vessel, for the reason that the space was so small that the ice would form a solid mass around the 25 journal and prevent the rotation of the vessel. I not only provide an increased surface for the action of the ice, but as the apex of the conical bottom forms the journal it is impossible for the ice to freeze around it so as to prevent 30 the rotation of the vessel.

Furthermore, my freezer is especially adapted for use on occasions such as summer picnics, &c., when the temperature is very high and it is necessary to rotate the vessel while the 35 cream is being served in order to prevent the melting of the same. It will be observed that the cross-head is some distance above the top of the vessel, and that the central sleeve, rising vertically from the lid of the vessel, passes 40 through the cross-head. In order, then, to raise the lid so as to permit the cream to be served, but at the same time have it in position to be quickly slipped back on the vessel, it is only necessary to shift the driving-shaft longitudinally in its bearing and then raise the lid, the 45 central vertical sleeve serving as a guide to

hold the lid directly over the top of the vessel. The lid may be held in its raised position by any convenient means, and when the desired quantity of cream has been removed from the 50 vessel the lid is dropped onto the same, the driving-shaft shifted into its former position, and the vessel can then be rotated, as will be readily understood. This feature of my invention is very advantageous, as I thereby 55 overcome and prevent the melting of the cream, which ordinarily arises when the vessel containing the same is frequently opened to permit removal of the cream.

Having thus described my invention, I 60 claim—

The improved ice-cream freezer herein described and shown, consisting of an outer vessel, A, having a flat bottom provided with a central socket in its upper face, the inner 65 vessel, C, having an inverted conical bottom with its apex resting in the socket in the bottom of the vessel A, the standards B B, secured to the sides of the outer vessel, A, and extending up above the same, the cross-head secured 70 upon the upper ends of the standards, the lid C' for the inner vessel, having a series of cog-teeth, K, on its upper side, the sleeve K' on the lid, projecting upward into the cross-head and movable through the same, the dasher 75 within the inner vessel, having its shaft N projecting upward through the sleeve K' and above the cross head, a latch on the cross-head adapted to engage the projecting end of the shaft N, the shaft L, journaled in one of the 80 standards and longitudinally movable in its bearing, and a pinion on the inner end of the said shaft engaging the teeth K on the lid, as set forth.

In testimony that I claim the foregoing as my 85 own I have hereto affixed my signature in presence of two witnesses.

CHARLES SPORNHAUER.
